THERAPEUTIC LAMP

Frank Furedy, Chicago, Ill.

Application May 31, 1955, Serial No. 36,284

Term of patent 14 years

(Cl. D48—20)

Fig. 1.

Fig. 2.

Fig. 1 is a front perspective view taken from the right of a therapeutic lamp embodying my new design and showing the lamp extended and the doors open; and

Fig. 2 is a front perspective view thereof taken from the left, showing the lamp retracted and the doors closed.

I claim:

The ornamental design for a therapeutic lamp, as shown.
